DISPENSING NOZZLE

Fritz Niesemann, Pittsburgh, Pa., assignor to
Pittsburgh Equitable Meter Company, Pitts-
burgh, Pa., a corporation of Pennsylvania

Application September 30, 1929, Serial No. 396,283

15 Claims. (Cl. 277—20)

The present invention relates to gasoline dispensing nozzles.

It is a recognized fact that certain types of gasoline measuring meters used in connection with pressure gasoline dispensing apparatus register inaccurately on flows below a predetermined minimum rate, which rate varies somewhat with various meters.

Hand operated dispensing nozzles are generally employed in connection with pressure gasoline dispensing apparatus. Said nozzles comprise valves by which the flow of gasoline is manually controlled. In nozzle constructions at present in common use, the hand operated control valves regulate the flow of gasoline at rates between the maximum flow and no flow and no means are provided for preventing a flow below the minimum at which the meter is accurate. Such nozzles can be manipulated by throttling the flow to a very low rate, so that the register of the meter will not give a reading showing the correct flow.

It is a primary object of the present invention to provide a gasoline dispensing nozzle whereby the above noted objections to existing nozzles are entirely overcome.

It is a further object of the invention to provide a gasoline dispensing nozzle comprising flow control means, said means adapted to insure a flow of gasoline above a predetermined rate whenever the valve is manipulated.

It is a still further object of the invention to provide a gasoline dispensing nozzle comprising a hand actuated flow control valve, and means associated with said valve for preventing a flow through the nozzle below a predetermined minimum rate.

It is a still further object of the invention to provide a gasoline dispensing nozzle comprising a main flow valve and a predetermined minimum flow valve, and manually operable means for successively operating said minimum flow valve and said main flow valve respectively.

It is a still further object of the invention to provide a gasoline dispensing nozzle comprising a flow control valve, hand actuated means associated with said valve, and quick acting means operatively connected with said hand actuated means for reflecting a predetermined minimum flow at a rate that is not variable with the amount of movement of said hand actuated means.

With the above objects in view as well as others that will become obvious during the course of the following disclosure reference will be had

to the accompanying drawing forming part of same and wherein:

Figure 1 is a longitudinal sectional view of a nozzle constructed in accordance with a preferred embodiment of my invention, certain parts being shown in elevation.

Figure 2 is a broken horizontal sectional view substantially on a plane represented by line 2—2 in Figure 1.

Referring to the drawing by reference characters in which like characters designate like parts 11 designates the nozzle body comprising the substantially long tubular portion 12 and a similar portion 13 disposed at an angle to portion 12 and communicating therewith. One end 15 of portion 12 is internally threaded for detachable connection therewith of an externally threaded end of a connecting member 14 whose opposite end is reduced and internally threaded, as indicated at 15, for detachable connection 20 therewith of one end of a flexible delivery hose. The free end of portion 13 is likewise internally threaded for detachable connection therewith of an externally threaded end of a connecting member 16 whose opposite end is reduced as 25 indicated at 17, for the reception of one end of the tank delivery tube 18, the connecting members 14 and 16 being respectively provided with flanges 18' and 19 for confining sealing gaskets 21 and 22 therebetween and the respective ends of portions 12 and 13. Suitably connected to and preferably integral with body 12 is a handle member 23 which is preferably connected with body 12 adjacent the ends of portions 12 and 13 and by means of which the nozzle is 35 conveniently transported.

The body portion 11 serves to convey the flow of gasoline from the hose to the delivery tube 18 by way of tubular portions 12 and 13. Said flow is controlled by a valve 24 carried by a valve stem 25 which adjacent the opposite ends thereof is mounted in bearings 26 and 27 permitting longitudinal movement of the valve stem. The stem 25 is provided with a flange 28 against which the valve 24 is detachably clamped by 45 means of a washer 29 held in engagement with valve 24 by means of a nut 31 engaging a threaded portion 32 of valve stem 25. Valve 24 is normally held in engagement with an inclined valve seat 33 formed in body portion 12 by 50 means of a helical spring 34 one end of which engages washer 29 and the opposite end of which engages a spider 35 which integrally connects bearing 27 with removable connecting member 14.

The valve stem 25 projects beyond flange 28 and is provided with a relatively long bore 36 opening through the end thereof and in which is slidably disposed a reduced portion 37 of a manipulating stem 38 which stem has slidable support in a gland structure 39 detachably threaded in the closed end of body portion 11. The gland structure 39 comprises a cup member 41 in which is disposed a leak proof packing 42 held 10 in fluid sealing engagement with stem 38 by means of a centrally bored plug 43 threadedly engaged within cup member 41.

The stem 38 is provided with a shoulder 44 at the junction of reduced portion 37 with the main 15 portion of stem 38, which shoulder forms an abutment for a spring end engaging cap 45, which cap is engaged by one end of a helical spring 46 the opposite end of which rests on a spider 47 which integrally connects bearing 26 with body 20 portion 11. The outer end of stem 38 engages a bead bearing portion 48 of a manipulating lever 49 pivotally connected at 51 to a bracket 52 integral with body 12, as well as to handle 23. The spring 46 normally maintains stem 38 in an outward 25 position with lever 49 in the position indicated in Figure 1 with the free end thereof in engagement with handle 23, as indicated at 53 providing a stop for the outward movement of stem 38 and in which position the free end of 30 reduced portion 37 of stem 38 is in substantial spaced relation to the bottom of bore 36 in stem 25, as indicated in Figure 1, whereby upon downward movement of stem 38 through actuation of lever 49 valve 24 will not be unseated until 35 stem 38 has moved so that the free end of portion 37 engages the bottom of bore 36, for a purpose hereinafter described.

The body portion 11 comprises further an integral hollow angular portion 55 interconnecting 40 tubular portions 12 and 13, and which, as indicated in Figure 1, defines a bypass around the flow control valve 24, said bypass comprising a relatively short bore 56 at right angles to tubular portion 12 and communicating therewith immediately inwardly of valve 24 and a second somewhat larger bore 57 at right angles to bore 56 and with which bore 56 is in communication adjacent the inner end thereof. The outer end of bore 57 is reduced, as indicated at 58. In said 50 reduced bore is disposed a valve stem guide sleeve 61. Slidably mounted in said sleeve is the outer end of a valve stem 62 which carries a valve 63 normally maintained in engagement with a valve seat 64, defined by bore 57 and reduced portion 55 59 by means of a helical spring 65 surrounding stem 62 with one end thereof engaging valve 63 and the opposite end engaging a plug 66 threadedly engaged in the inner end of bore 57 and provided with a guide bore 67 for the inner end of 60 stem 62.

The valve 63 controlling the flow through the by-pass is adapted to be unseated prior to the unseating of valve 24 in order to provide a flow of gasoline at a predetermined minimum rate so 65 that a flow below this minimum rate cannot occur. In order to provide a predetermined minimum flow it is essential that valve 63 be opened upon initial movement of lever 49 and in order to effect this the construction embodies the following additional mechanism. A pivot pin 69 is disposed within body portion 11. Said pin is removably secured therein by means of a threaded enlarged portion 71 threadedly engaged within a threaded bore 72 in body portion 11. Pivotally supported on pin 69 are the inner adjacent ends

of a pair of levers 73 and 74 which with pin 69 define a toggle arrangement. The levers 73 and 74 are supported on pin 69 immovably longitudinally thereof by means of a stop ring 75 detachably secured to pin 69 adjacent the free end thereof by means of a set screw 76. Spacing collars 77 and 78 are disposed on pin 69 between levers 73 and 74 and ring 75 and threaded portion 71 respectively. The spacing mechanism further comprises a relatively thin spacing ring 79 disposed between levers 73 and 74. The levers 73 and 74 are of angular formation in plan, as indicated in Figure 2, and are provided with ears 73' and 74' respectively, to which ears are detachably connected the opposite ends of a tensioned helical spring 81, which normally maintains levers 73 and 74 in angular relation as indicated by full lines in Figure 1 with spring 81 disposed above the axis of pin 69. The levers 73 and 74 are limited in this angular position by 10 means of a pin 82 carried by stem 38 and projecting into an elongated slot 83 in lever 73 and by the engagement of the outer end of a stop member 84 secured to lever 74 with the inner wall of tubular portion 13, the stop member projecting 15 inwardly of lever 74 as indicated at 86 for a purpose later described.

In operation of the nozzle construction disclosed handle 23 is grasped by the hand of an operator who with his fingers moves lever 49 about its pivot 51, which lever through engagement of head 48 with stem 38 moves same downwardly, and as stem 38 moves downwardly lever 73 is moved downwardly about pin 69 by means of pin 82 which projects through slot 83 and lever 74 will remain in its normal inactive position illustrated by full lines in Figure 1 until lever 73 has been moved downwardly a distance such that the direction of pull of spring 81 is below the axis of pin 69 at which instant lever 74 will be drawn 30 downwardly by spring 81 with a snap action whereupon projection 74" of lever 74 will engage stem 62 resulting in a complete unseating of valve 63 thus establishing an instantaneous predetermined flow of gasoline through the by-pass 35 defined by bores 56 and 57. The valve 63 will be unseated in the manner above described before valve 24 begins to open due to the lost motion connection between stem portion 37 and stem 25 by means of the bore 36 in which stem 37 is 40 movable and whose free end is normally spaced from the bottom of said bore. The normal distance however, between the free end of stem portion 37 and the bottom of bore 36 is such that valve 24 begins to open immediately after opening of valve 63 by the toggle mechanism above disclosed upon continued movement of lever 49 resulting in a flow of gasoline directly through tubular portions 12 and 13 together with the bypass flow above referred to. The lever 73 upon 45 continued downward movement of stem 38 moves therewith through the pin and slot connection 82 and 83 while lever 74 remains in the position indicated by dot and dash lines in Figure 1 with projection 86 of stop member 84 in engagement 50 with the inner wall of tubular portion 13.

Upon releasing lever 49 valve 24 will be forced to its seat by spring 34 with levers 73 and 74 still in their angular position indicated by dot and dash lines in Figure 1 and with valve 63 still 55 open but upon continued release on lever 49 stem 38 will be forced upwardly by spring 46 and as stem 38 thus moves upwardly lever 73 will be moved upwardly by engagement of pin 82 with a wall of the slot 83 therein until the longitudinal 60

axis of spring 81 is again above the axis of pin 69 instantaneous with which lever 74 will be thrown upwardly with a snap action to the position indicated by full lines in Figure 1 whereupon valve 63 will be quickly closed by means of spring 65.

It will accordingly be seen that with the improved nozzle construction disclosed gasoline cannot be dispensed at a rate of flow below a predetermined minimum or within the accuracy range of the meter as valve 63 will open or close instantaneously by means of the toggle mechanism disclosed regardless of the rate of movement imparted to lever 49 due to the snap action feature of the toggle mechanism which is actuated by lever 49 and which controls valve 63.

In order to provide adjustment in the by-pass flow, externally threaded plugs 91 having various sized orifices 92 may be provided and any one of which according to the desired by-pass flow is removably threaded into an internally threaded enlargement 93 of bore 56. In order to insert or remove plug 91 same is inserted or withdrawn through the bottom of bore 57 upon removal of plug 66 and in order to thread plug 91 into position a threaded opening 94 is provided opposite bore 56 for insertion of a suitable tool, the opening 94 being normally closed by a threaded plug 95.

While I have disclosed but a single specific embodiment of my invention, same is to be considered as illustrative only and not restrictive since the scope of the invention is defined by the subjoined claims rather than the foregoing specific disclosure.

What I claim and desire to secure by U. S. Letters Patent is:—

1. A dispensing nozzle comprising a body designed to permit the flow of fluid therethrough in two passages, a valve controlling each passage, manually operable means connected to one of said valves so that said means can move relative to said valve before causing the valve to be moved, and mechanism for the other of said valves, said mechanisms being connected to said manually operable means so that said last named valve is opened with snap movement after a predetermined initial movement of said manually operable means before it actuates said first named valve.

2. A dispensing nozzle comprising a body designed to permit the flow of fluid therethrough in two passages, a valve to control the flow in each passage, manually operable means arranged to actuate one of said valves, said means being connected to said valve so that it may be operated substantially without affecting said other valve, a pivoted arm within said body arranged to actuate the valve controlling the other of said passages, a second pivoted arm extending away from said first named arm, a spring acting to draw said arms toward each other, means to limit the swinging movement of said arms, and means connecting one of said arms to said manually operable means, said last named means being arranged so that said arms are actuated to cause said spring to shift the line of its action from one side of the axis to the other side thereof to open the valve actuated thereby prior to the opening of the valve connected to said manually operable means.

3. A dispensing nozzle comprising a body having a passage to permit the flow of fluid therethrough, a valve to control said flow, a pivoted arm arranged to actuate said valve, a second

pivoted arm extending away from said first named arm, a spring acting to draw said arms toward each other, means to limit the swinging movement of said arms, and manually operable means to actuate said second arm to cause said spring to shift its line of action from one side of the pivotal axes of said arms to the other side thereof, whereby said first named arm is shifted with a snap action under the influence of said spring so that the valve movement is not proportional to the movement of said manually operable means, the said body being formed with a second passage therethrough, a valve to control the flow through said second passage, and means to connect said manually operable means to said last named valve so that said valve is operable after the actuation of the valve actuated by said pivoted arm.

4. In a compound valve structure, a body with a passage for fluid, a valve to control the flow of fluid through said passage, a separate by-pass exterior to said passage, a valve for controlling said by-pass means for jointly actuating said valves, said means first opening the valve in the by-pass with a snap action and then upon further actuation, opening the valve in the main passage.

5. A manually controlled dispensing nozzle adapted to positively prevent flow therethrough below a predetermined minimum rate and to allow a regulated flow above the minimum comprising a valve body having two passages of different size, a valve in each passage to control the flow therethrough, and manually operable means to operate said valves, including means to open and close the valve in the smaller passage with a snap action.

6. The invention as defined in claim 5 wherein the said means opens the valve in the smaller passage before opening the valve in the larger passage.

7. A valve mechanism adapted to positively prevent flow below a predetermined minimum rate and to allow a regulated flow above the minimum comprising a valve body having a main passage therethrough, a valve to control the flow of fluid through said passage, a smaller by-pass passage, a by-pass valve to control flow of fluid through said by-pass passage, a valve operating mechanism having a lost motion connection with said main passage valve, a double snap device for operating said by-pass valve to thereby maintain said valve fully open or fully closed, and a connection between said valve operating mechanism and said snap device to open said by-pass valve before any movement of the main valve and to fully close said main valve prior to closure of the by-pass valve.

8. The invention as defined in claim 7 wherein said double snap device is positioned within said valve body.

9. The invention as defined in claim 7 wherein said valve operating mechanism is adapted to vary the flow through said main passage by varying the position of the main valve after the predetermined minimum flow has been established through said by-pass by the full opening of the by-pass valve.

10. A dispensing nozzle comprising a body providing a passage for fluid, a valve to control the flow of fluid through said passage, a by-pass around said valve, a valve to control the flow of fluid through said by-pass, means to manually operate said first named valve and mechanisms operable by said means to actuate said by-pass valve with a snap action in advance of the opera-

tion of said first named valve and to hold said by-pass valve open while the first named valve is open.

11. The combination as defined in claim 10, 5 including means arranged in said by-pass and readily movable therefrom to vary the predetermined minimum rate of flow through the by-pass.

12. A dispensing nozzle comprising a body 10 designed to permit the flow of fluid therethrough in two passages, valve means to control each passage, and manually operable means connected to said valve means so that one of said passages is opened with a snap action in advance of the opening of the second of said passages, the first passage 15 remaining open while the second named passage is open and closing after the second named passage is closed.

13. A device of the character described, comprising in combination, a casing having an inlet 20 and an outlet, and means for controlling flow from said inlet to said outlet, said means comprising a valve positioned between said inlet and outlet, an operating member, a lost motion connection therebetween, a second valve positioned 25 between said inlet and outlet, and means actuated

by movement of said operating member to take up said lost motion for causing said second valve to open a predetermined amount.

14. The combination with a valve body, of a plurality of valves therein for controlling the flow 5 of fluid through said body one being a main valve and another being an auxiliary valve, and actuating means common to said valves and adapted to actuate the same in succession including a lost motion connection for operating the main valve 10 and snap action means for operating the auxiliary valve.

15. In a dispensing nozzle comprising a plurality of fluid passages therethrough, valves for closing said passages, a single manually operable means for actuating said valves, means for providing a predetermined minimum flow through one of said passageways when the valve thereof is opened in dispensing fluids, said manually operable means being arranged to regulate the rate of flow through another of said passages through a second of said valves above the said minimum flow. 15

FRITZ NIESEMANN. 25
